UNITED STATES PATENT OFFICE.

GAYLE L. SQUIRE, OF HASTINGS, FLORIDA.

LADDER.

Application filed December 1, 1922. Serial No. 604,302.

To all whom it may concern:

Be it known that I, GAYLE L. SQUIRE, a citizen of the United States, residing at Hastings, in the county of St. Johns and State of Florida, have invented a new and useful Ladder, of which the following is a specification.

This invention relates to ladders, and more particularly to folding ladders.

10 The object of the invention is to provide a ladder of this character constructed to be used as a straight ladder, as a step ladder, or as a trestle and which when folded, can be stored in a small space.

15 Another object of the invention is to provide a folding ladder, the sections of which are hingedly connected and equipped with slideable locks to hold the sections rigid when in longitudinal alinement and shiftable to 20 permit them to fold for use as a step ladder or to be collapsed for storage.

With the foregoing and other objects in view which will appear as the description proceeds, the invention resides in the combination and arrangement of parts and in the details of construction hereinafter described and claimed, it being understood that changes in the precise embodiment of the invention herein disclosed may be made 30 within the scope of what is claimed without departing from the spirit of the invention.

In the accompanying drawings:—

Figure 1 represents a side elevation of the ladder constituting this invention shown in 35 position for use as a step ladder.

Fig. 2 is a front elevation thereof.

Fig. 3 is a longitudinal section taken on the line 3—3 of Fig. 2.

Fig. 4 is a detail side elevation of the 40 ladder with the sections extended and locked in longitudinal alinement, and

Fig. 5 is a detail transverse section taken on the line 5—5 of Fig. 4.

In the embodiment illustrated, the ladder 45 constituting this invention is composed of two sections 1 and 2, the side bars 3 of which are hingedly connected at their inner ends as shown at 4. The hinged ends of these sections are equipped with slideable locks 5 which are constructed exactly alike and hence one only will be described in detail.

These locks each comprises a plate 6 countersunk in one side face of one of the section bars and secured thereto by any 55 suitable means. A stud or stud shaft 7 pro-

jects laterally outward from the outer face of this plate and is designed to pass through a slot 11 in a casting 10 which constitutes the sliding member of the lock and which is secured in sliding engagement therewith 60 and held in place by a cotter pin 9.

The sliding casting 10 is provided along one edge thereof with laterally extending lugs 12 and 13 designed to overlie and slidably engage the edges of the bars 3 of the 65 ladder sections as is shown clearly in Figs. 1, 2 and 4. The lug 13 at the inner end of the casting has an inturned flange 14 to slidably engage the inner face of the side bars on which it operates. This casting is also 70 provided at its inner end with an aperture 15 designed to register when the sections 1 and 2 are in opened straight out position with a cooperating aperture 16 formed in the adjacent ladder section so that when the 75 sliding casting 10 is moved to bridge the joint between the sections, the aperture 15 therein will register with the aperture 16 to receive a securing pin 17 carried by a chain 18 attached at one end to the section 1. 80

It will thus be seen that when these locking castings 10 are shifted to bridge the joints between the sections and are secured by the pins 17, the sections will be rigidly held against folding to adapt the ladder 85 for use as a straight ladder.

When the ladder is to be used as a step ladder, or to be folded for storage, the sliding castings 10 are shifted longitudinally into the position shown in Figs. 1, 2 and 3, 90 it of course being understood that the pins 17 are first withdrawn. When these castings are so shifted, the sections 1 and 2 may be swung on their hinges and when desired for use as a step ladder are secured in substantially A-shaped form by means of brace rods 19 which are pivotally connected at one end to the side bars of one section and provided at their free ends with hooks as 20 adapted to be engaged with keepers 21 carried by the opposed sections so that the sections will be securely held in the position shown in Fig. 1 for use as a step ladder. 100

Spring clips 22 are mounted on the inner faces of the side bars to which the rods 19 are secured, and are designed to yieldably hold said rods when not in use to prevent them swinging and dangling around, as is shown clearly in Fig. 3.

The side bars of section 1 are provided on 110

their inner faces near their lower ends with snap hooks 23, which when the ladder is in folded position are designed to engage the keepers or eyes 21 of the adjacent section 5 whereby the sections are securely held in collapsed position ready for storage.

The flanges 14 of the legs 13 are also apertured as shown at 14^a, said apertures registering with the apertures 15 in the castings so that when these castings are shifted into the position shown in Fig. 4, the pin 17 will pass through the end of the casting, through the side bar of the ladder section and through the flange 14, and thus securely 15 lock the sections against separating as well as against folding movement.

From the above description it will be obvious that this ladder may be quickly set up for use as an extension or straight ladder by shifting the castings 10 in the manner above described, or it may be folded for use as a step ladder opening up the sections and securing them by the brace bars 19 and when desired to fold the ladder for 25 storage, the brace bars 19 are disengaged from the keepers 21 and swung into the position shown in Fig. 3, being held by the clips 22. The snap hooks 23 are then engaged with the eyes of keepers 21 and hold

the sections in folded position ready for 30 storage.

I claim:—

In a ladder, sections hingedly connected at one end to open into alinement to form a straight ladder and foldable for use as a step 35 ladder, a plate counter-sunk in one side face of one section and fixed thereto, a stud projecting laterally from said plate, a longitudinally slotted casting slidable on said plate with said pin projecting through said 40 slot and having lateral lugs to overlie the edge of the bar on which the casting is mounted, said casting having an aperture and one of said lugs having an inturned 45 flange apertured to register with the aperture in the casting, the other ladder section having an aperture to register with said casting apertures when the casting is moved to bridge the joint between the sections, and a pin to enter said registering apertures to 50 lock the sections in open position.

In testimony that I claim the foregoing as my own, I have hereto affixed my signature in the presence of two witnesses.

GAYLE L. SQUIRE.
